UNITED STATES PATENT OFFICE.

WALLACE P. GROOM, OF BROOKLYN, NEW YORK.

ARTICLE OF WEARING-APPAREL PROVIDED WITH BUTTON-HOLES.

SPECIFICATION forming part of Letters Patent No. 320,131, dated June 16, 1885.

Application filed April 3, 1885. (No model.)

To all whom it may concern:

Be it known that I, WALLACE P. GROOM, of the city of Brooklyn, in the county of Kings and State of New York, have invented a new 5 and useful Improvement in Articles of Wear- ing-Apparel Provided with Button-Holes, of which the following is a specification.

My invention is applicable more particu- 10 larly to collars and cuffs, but may be embodied in other articles, the particular object being to facilitate the insertion of buttons and other fastening devices into collars, cuffs, and other articles, and also to facilitate their withdrawal when desired.

15 The invention is, among other things, in- tended for cuffs and collars made wholly or in part of chrolithion or other pyroxylene com- pound, or of paper, but may also with special 20 advantage be embodied in linen goods which are to be starched or stiffened, and in other articles.

25 The invention consists in an article of wear- ing-apparel provided with a button-hole hav- ing in one of its edges or lips a notch or re- cess, and having at its end an eyelet-hole or 30 enlargement. The notch or recess receives the shank or base of a button which is to be inserted in the button-hole, and the eyelet or enlargement at the end of the button-hole gives 35 flexibility to the lips or edges, and there- by facilitates the insertion of a button or stud into the button-hole and its removal there- from.

35 The button-hole may consist of a slot uni- form in width, save at the notch or recess and eyelet-hole or enlargement; or the button-hole may consist of a slot of sufficient width to receive the shank of a button, having at one end the eyelet or enlargement and at the other end 40 the notch or recess, and a narrow slit extending beyond the notch or recess to form the necessary length of button-hole desired.

45 In the accompanying drawings, Figure 1 represents a cuff having button-holes embody- ing my invention. Fig. 2 represents a sec- 50 tional view of a portion of a cuff with a sleeve- button in the position which it occupies while being inserted in the button-hole. Fig. 3 rep- resents a plan of the parts shown in Fig. 2, and Fig. 4 represents the end portions of a 55 collar having button-holes embodying my in- vention.

Similar letters of reference designate corre- sponding parts in all the figures.

A designates a cuff embodying my inven- 55 tion, and B B designate the two end portions of a collar also embodying my invention. The length of the cuff is reduced in the drawings.

C C' C² designate button-holes in the cuff, 60 which are slightly different in form, but all of which embody the essential features of my in- vention.

The button-hole C consists of a slot formed by removing a portion of the material or fab- 65 ric, and has in one of its edges or lips, c, a notch or recess, a, at about midway of the length of the button-hole. The other lip or edge, c', is straight throughout, and at the end of the button-hole is an eyelet-hole or enlarge- 70 ment, c², formed by removing a portion of the fabric.

The button-holes C' have in one edge of the 75 lip c a notch or recess, a, as above described, and have the other edge or lip plain or straight, like the button-hole C; but the button-holes C' differ from the button-hole C in that only the portion extending from the notch or recess a to the eyelet-hole or enlargement c² consists of a slot, while the portion on the other side of the notch or recess consists only of a slit, and 80 is formed without the removal of any mate- rial.

The button-hole C² consists of a curved or 85 arc-shaped slot of approximately uniform width throughout, having in its convex lip or edge c a notch or recess, a, and having an eye- 90 let-hole or enlargement, c², at the outer end of the button-hole. The eyelet-hole or enlarge- ment c² will have its center in line with the center line of the button-hole, or may be off- set entirely to one side thereof.

In Fig. 1 the button-holes C C² represent the eyelet-hole or enlargement c² as formed in the center line of the button-hole, and the button- 95 hole C' at the lower left-hand corner of the cuff represents a similar position of the eye- let-hole or enlargement c². In the button-hole C' at the upper right-hand corner of the cuff the eyelet-hole or enlargement c² is represented as offset toward the lip or edge c, and has its 100 circumference tangential with the lip or edge c'. The ends of the collar B (represented in Fig. 4) have in them button-holes C', which are 105 similar to that shown in Fig. 1—that is to say,

these button-holes have the eyelet-holes or enlargements c^2 tangential to the lips or edges c' of the button-holes.

When the sleeve-button D is to be inserted 5 into the holes in the cuffs, it will be placed in the position shown in Figs. 2 and 3. In this position the shank d of the button is received in the notch or recess a , and the eyelet-hole or enlargement c^2 at the end of the button-hole o gives the lips or edges c c' sufficient elasticity to enable the back plate, d' , of the button to be readily pushed past the lip or edge c' . For a like reason the eyelet-hole or enlargement c^2 facilitates the removal of the sleeve-button D 5 from the button-hole.

It will be observed that in all the examples of my invention here shown the button-hole has in one lip or edge a notch or recess, a , and has at its end an eyelet-hole or enlargement, c^2 , which both of them combine to facilitate the ready insertion of a button into the button-hole or its removal therefrom.

What I claim as my invention, and desire to secure by Letters Patent, is—

1. An article of wearing-apparel provided 25 with a button-hole having in one lip or edge a notch or recess, a , and having at its end an eyelet-hole or enlargement, c^2 , substantially as and for the purpose herein described.

2. An article of wearing-apparel provided 30 with a button-hole having in one lip or edge a notch or recess, a , and having at its end the eyelet-hole or enlargement c^2 , that portion of the button-hole between the notch or recess and enlargement consisting of a slot to accommodate the shank of a button, and that portion of the button-hole extending on the opposite side of the notch or recess consisting of a narrow slit, substantially as and for the purpose herein described.

WALLACE P. GROOM.
